UNITED STATES PATENT OFFICE

110,512

DESIGN FOR A BOX

Edward L. Arneson, Morris, Ill., assignor to Morris Paper Mills, Chicago, Ill., a corporation of Illinois

Application May 5, 1938, Serial No. 77,011

Term of patent 3½ years

To all whom it may concern:

Be it known that I, Edward L. Arneson, a citizen of the United States, residing at Morris, in the county of Grundy and State of Illinois, have invented a new, original, and ornamental Design for a Box, of which the following is a specification, reference being had to the accompanying drawing, forming part thereof, wherein

Fig. 1 is an elevational view of a box embodying my new design;

Fig. 2 is a top view of same, on a smaller scale; and

Fig. 3 is a bottom view of same.

I claim:

The ornamental design for a box substantially as shown.

EDWARD L. ARNESON.
